(57) **CLAIM**

The ornamental design for a transmission mock-up assembly as shown and described.

DESCRIPTION

FIG. 1 is a perspective view of the transmission mock-up assembly.

FIG. 2 is a left view of the transmission mock-up assembly.

FIG. 3 is a right view of the transmission mock-up assembly.

FIG. 4 is a top view of the transmission mock-up assembly.

FIG. 5 is bottom view of the transmission mock-up assembly.

FIG. 6 is a front view of the transmission mock-up assembly; and,

FIG. 7 is a back view of the transmission mock-up assembly.
